A. AMSLER

COLLAPSIBLE CONTAINER

Original Filed Nov. 7, 1924

UNITED STATES PATENT OFFICE.

AUGUST AMSLER, OF BERN, SWITZERLAND, ASSIGNOR TO EWAK A.-G., OF BERN,
SWITZERLAND, A SWISS CORPORATION.

COLLAPSIBLE CONTAINER.

Original application filed November 7, 1924, Serial No. 748,477, and in Switzerland November 15, 1924.
Divided and this application filed April 20, 1926. Serial No. 103,241.

My invention relates to a collapsible container for handling piece goods in bulk, as for example such articles as postal packages, pieces of baggage and the like. The 5 present invention is a division of my co-pending application for patent Serial No. 748,477 filed November 7th, 1924.

My improved container is primarily although not exclusively designed for use in 10 the postal service. Aside from the fact that in the postal service certain smaller articles are packed in sacks and boxes and are handled in that manner, the greatest number of articles handled by the postal authorities are presented singly.

It has been heretofore proposed to pack these articles in large boxes and rigid containers, and to handle the latter by means of suitable hoisting gear and the like, but 20 it has been found in practice that the use of such boxes and rigid containers is unsatisfactory, due largely to the fact that the boxes and containers are not well adapted to receive an assortment of articles variegated 25 as to size and shape, and because such boxes and containers take up very considerable space and interfere with the work of the personnel, particularly in mail trains, baggage cars and the like. Moreover the boxes 30 and rigid containers are fairly heavy as a rule and are undesirable for that reason.

The principal object of my invention is to provide a container which will occupy comparatively little space, is comparatively light 35 in weight, and is flexible in the sense that it may receive large quantities of a great variety of differently shaped articles of varying dimensions and can be easily handled manually or by machinery.

40 The essential characteristics of my container is that it has two oppositely disposed flexible movable sides. While the container is being filled these side walls are maintained in upright position by means of rods 45 or bars which may thereafter be connected with the open sides to form the open ends of the container. After the container has been filled it may be secured about its contents by having certain parts of the sides secured 50 together, and a certain amount of play is allowed for the contents by reason of the flexibility of the container. Play is also permitted lengthwise of the container so that no

matter how irregular the assembly of packages may be, the container nevertheless will 55 retain all the articles in position.

Whether the container is entirely filled or only partly filled its sides may be secured about its contents so that in this sense the container is flexible. The container 60 adapts itself to the size and shape of the articles therein, its weight is comparatively small as compared with its contents and when collapsed the container occupies very little more space than its base. 65

The invention is illustratively exemplified in the accompanying drawing, in which Figure 1 is an end elevation of the container in extended position; Fig. 2 is a side elevational view; Fig. 3 is a perspective view of 70 a filled container constructed in accordance with my invention; and Fig. 4 is a detail sectional view of the arrangement of the bars at a corner of the container.

Referring to the drawing, 2 denotes a 75 substantially rectangular base mounted on feet or rollers 1. It is desirable to have the base 2 as light as possible and for that reason it may be constructed of wood or other light material.

At each of the longer sides of the base 2 I provide a plurality, preferably four, of ropes 3 which are provided at uniformly spaced intervals with eyes 3'. One end of 80 each rope is desirably secured to the base, the attachment of the ropes to the base being releasable, if desired, although not necessarily so.

The ropes 3 on each side of the base 2 are interconnected by inserting a plurality, 85 preferably five, parallel bars 4 through the eyes 3' of the ropes so that the bars with the ropes form a movable and flexible side of the container.

In order to hold these sides erect while the container is being filled four rods 5 which serve as corner posts are provided, these rods being offset at their ends and designed to be inserted in holes at the four corners of the base 2, as shown in dotted 90 lines in Figures 1 and 2.

The bars 4 are provided with eyes 6 at their ends, and in erecting the container the eyes of the upper bars 4 are placed over the offset ends of the corner posts 5. The 100 articles to be handled are placed on to the 105

base 2 between the upright flexible sides provided by the ropes 3 and bars 4. The articles may be introduced into the container from its two open ends, and these articles may vary in size, shape and weight, and very great quantities thereof may be received by the container without overloading it. Its capacity varies within very wide limits because of the flexible and open character of the sides.

After the container has been filled the upper bars 4 are removed from the corner posts 5 and the middle ropes 3 of both sides are placed together over the top of the load and are then interconnected by a strap, clip or latch 7. The four corner posts 5 then are withdrawn from the holes in the base 2 and their ends are inserted in the eyes 6 of two complementary bars 4 of the two longer sides to form open ends for the container. As shown in Fig. 4, the offset ends of the corner posts 5 have each a groove 8 containing a spring latch 9, which may engage in the rear of the eye 6 and thus prevent unintentional separation of the connection between the transverse rods 5 and the bars 4. This connection may be released by pressing the latch 9 inwardly, but it will be understood that any equivalent of the spring latch 9 may be used. The transverse rods 5 do not prevent the contents of the container from projecting beyond the normal vertical plane of that side of the base at which the rods 5 are positioned so that what may be loosely termed a considerable overload, may be carried by the container without danger of loss of articles.

In collapsed condition, the corner posts 5 may be laid on the base 2, the flexible sides folded on the base and then secured by the straps 7, so that the entire container occu-

pies substantially no greater amount of space than the area of its base 2.

I claim:—

1. A collapsible container, comprising a base member having openings, oppositely arranged flexible sides attached thereto, said sides comprising ropes connected by bars, and corner posts insertible in the openings and removable therefrom for temporarily retaining said sides in erect position.

2. In a collapsible container, the combination with the elements claimed in claim 1, of means carried respectively by said sides and said corner posts for releasably interconnecting the same.

3. A collapsible container comprising a base member, flexible sides connected to said base member, said sides comprising a plurality of ropes and interconnected rigid bars, corner posts detachably connected to the base member and cooperating with the ends of the rigid bars in one position, said posts being removable for connection with the ends of certain of the rigid bars to form the open ends of the container.

4. A collapsible container comprising a base member, flexible sides connected to said base member, said sides comprising a plurality of ropes and interconnected rigid bars, eyes formed at the ends of said bars, corner posts detachably connected to the base member and insertible through the eyes of the rigid bars comprising the sides of the container, said posts being removable for connection with certain of the rigid bars to form the open ends of the container and a fastening element connecting the ropes of opposite sides of said container.

In testimony whereof I affix my signature.

AUGUST AMSLER.
